PHONOGRAPH PICKUP ARM CONTROL
MECHANISM

Jerald D. Weaver, Fort Wayne, Ind., assignor to
Farnsworth Television and Radio Corporation,
a corporation of Delaware

Original application December 6, 1941, Serial No.
421,891. Divided and this application January
11, 1943, Serial No. 471,943

4 Claims. (Cl. 274—10)

This invention relates to an automatic phonograph and more particularly to a mechanism for controlling the pickup arm thereof, whereby a mixed assortment of ten or twelve-inch records may be automatically reproduced. This application is a division of my application Serial No. 421,891, filed December 6, 1941, U. S. Patent No. 2,348,506, granted May 9, 1944, for Automatic record-changing mechanism.

In conventional pickup arm control mechanisms such, for example, as shown in U. S. Patent No. 2,286,490, granted June 16, 1942, the pickup arm is pivotally mounted for vertical and horizontal movement on a rotatable shaft which is rotatably supported by a pedestal fixed to the base plate at one side of the turntable. The rotatable shaft extends below the base plate and has a lever affixed to its lower end, which is engaged and moved through a predetermined arc by a movable member. This movable member is controlled by a cam wheel and normally moves through a predetermined cycle to return the pickup arm into engagement with the initial playing groove of a ten-inch record. When a twelve-inch record is moved into playing position, the movement of the movable member is arrested when it has swung the pickup arm inwardly to a position over the initial groove of the twelve-inch record.

This is generally accomplished by a mechanism which is associated with the record-supporting means and the cam wheel. When a twelve-inch record is released from its support, this mechanism is actuated and it functions to intercept or arrest the movement of the movable member when it has swung the pickup arm inwardly to a position immediately over the initial groove of a record.

Other types of mechanisms are provided for positioning the pickup arm in engagement with the initial playing groove of a twelve-inch record. For example, the mechanism shown in U. S. Patent No. 2,313,262, granted March 9, 1943, comprises a pivoted lever mounted on the top side of the base plate, adapted to be engaged by the pickup arm as it is swung inwardly and designed to engage the peripheral edge of a twelve-inch record when the pickup arm is moved inwardly to a position immediately over the initial groove of the record.

Each of the above types of pickup arm control mechanisms is expensive in construction and requires considerable space and frequent adjustment.

The object of the present invention is to provide improved pickup arm control mechanism for

accurately positioning a pickup arm over the initial playing grooves of records of different sizes.

In accordance with the present invention, there is provided an automatic phonograph which has a rotatable turntable for supporting a record thereon, a pickup arm and a controlling mechanism for the pickup arm. The controlling mechanism comprises means for elevating the pickup arm above the record on the turntable and lowering it into engagement therewith, means for moving the pickup arm outwardly beyond the periphery of the record on the turntable and returning it toward the center of the turntable, a lever movably connected to the pickup arm and adapted to be moved by the pickup arm elevating means relative to the pickup arm in a plane parallel to the axis of the turntable, and a projection on the lever for engaging the peripheral wall of the record on the turntable for stopping the return movement of the pickup arm. The projection is adapted to move out of engagement with the peripheral wall of the record on the turntable when the pickup arm is moved into engagement with it.

For a better understanding of the invention, together with other and further objects thereof, reference is made to the following description taken in connection with the accompanying drawings, and its scope will be pointed out in the appended claims.

In the accompanying drawings:

Fig. 1 is a top plan view of the pickup arm mechanism shown partly in section;

Fig. 2 is a fragmentary view, partly in section, showing the mechanism for moving and positioning the pickup arm; and

Fig. 3 is a fragmentary view on line 3—3 of Fig. 2, partly in section, with parts 52, 54 and 57 omitted, showing the mechanism actuated by the pickup moving mechanism while moving the pickup arm to its outermost position, which functions to move the pickup arm inwardly from its outermost position.

Referring now particularly to Figs. 1 and 3 of the drawings, the invention here illustrated shows a pickup arm control mechanism which includes a base plate 1 with a well 2 formed therein. A supporting bracket 3 is suitably affixed to the underside of the base plate 1 and is adapted to support tubular bearing element 4. The upper end of the bearing element 4 is provided with a flanged portion 5 which in turn is provided with a race for guiding a plurality of ball bearings 6 as shown in Fig. 2. The ball bearings 6 are adapted

to rotatably support a flanged tubular shaft 7 by engaging the bottom of the flanged portion thereof. The tubular portion of the shaft 7 extends downwardly into the tubular bearing element 4. A turntable 11 is fixed to the flanged portion of the shaft 7 to rotate therewith as shown in Fig. 2. A stack of records 12 may be supported on the turntable 11 and the records are maintained in a centered position by a spindle 10 rotatable with the turntable 11. Teeth 8 are provided on tubular element 4 for the purpose of elevating and lowering the turntable as is fully explained in United States Patent No. 2,348,506, granted May 9, 1944. The turntable may be driven by any suitable mechanism such as, for example, that disclosed in United States Patent No. 2,012,185, granted August 20, 1935.

A pickup arm 13 is mounted for vertical and horizontal movement on a pedestal 14 which is fixed to the base plate 1 at one side of the turntable 11, as shown in Fig. 1. For example, see U. S. Patent No. 2,313,262, granted March 9, 1943. At the free end of the pickup arm 13 there is provided a reproducer or a pickup 15 with a stylus 16 for cooperating with a record on the turntable to reproduce the record, as shown in Fig. 1.

Intermediate the ends of the pickup arm 13 there is pivotally connected thereto a lever 17, shown in Figs. 1 and 3. To one end of the lever 17 there is affixed a downwardly extending pin 18. A spring 20 is connected to the lever 17 in the manner shown in Fig. 2 to maintain the lever 17 in the full-line position shown in that figure. For supporting lever 17, there is provided a pivot pin 19 which extends through a pair of turned-down ears 17' on lever 17 into the side walls of pickup arm 13. The convolutions 21 of spring 20 are supported by pin 19 whereby to anchor the spring. As will be evident from the following description, when the raised pickup arm 13 is moved from its outermost position toward the turntable 11 and the uppermost record on the turntable is a 12-inch record, the pin 18 will extend into the plane of the 12-inch record, and serve to position the stylus 16 of the pickup arm 13 over the initial playing groove of that record.

The end of the pickup arm 13 that rests on the pedestal 14 has connected thereto a tubular shaft 22 which extends downwardly through the pedestal 14 and below the base plate 1. A lever 23 is keyed by threaded member 25 or otherwise fixed to the lower end of the shaft 22 in such a manner that the lever 23 is adapted to move a predetermined distance relative to the shaft 22 in a vertical plane and will move with the shaft 22 in a horizontal plane. Fig. 2 shows one way of associating the lever 23 and the shaft 22 to achieve these functions. The free end of the lever 23 has affixed thereto a downwardly extending pin 24. There is provided a cam surface 26 on a cam wheel 27 for engaging pin 24 and imparting horizontal movement thereto. The cam wheel 27 is fixed to a shaft 28 which is rotatably mounted in a suitable bracket 29 fixed to the bottom of the base plate 1. The shaft 28 may be driven by any suitable motor and gear mechanism known in the art such, for example, as that shown in United States Patent No. 2,012,185, patented August 20, 1935.

The upper end of the tubular portion of the lever 23 has affixed thereto an ear 30. A lever 31 is connected to the shaft 22 above the tubular portion of the lever 23 in a suitable manner so that the lever 31 may be moved in a horizontal plane relative to the shaft 22. The end of the

lever 31 which is connected to the shaft 22 is of tubular construction and the lower end thereof is notched at 32 in such a manner that the ear 30 may come into engagement therewith for rotating with the lever 31 in a horizontal plane. When the lever 31 is moved in a counterclockwise direction from the position shown in Fig. 3, it moves therewith the lever 31 in the same direction.

As shown in Fig. 3, a member 33 is pivotally supported by a bracket 34 which may be secured in a suitable manner to the bottom of the base plate 10. The member 33 is maintained in the position shown by a spring 36 connected to the bottom of the base plate 1 as at 35 and to the member 33. The member 33 corresponds to member 92 in the above-identified copending application and its function is fully described therein. The free end of the pivotal member 33 is connected to one end of a member 37 by a connecting link 38. Intermediate its ends the member 37 is pivoted as at 39 in a suitable manner to the base plate 1. The opposite end of the pivotal member 37 is connected to lever 31 by a spring-biased coupling member 40 pivotally connected to member 37, and member 41. The compression member 41 includes a tubular member 42, one end of which is connected in a suitable manner to the member 40, and the other end of which is connected to a pin 44. The pin 44 is provided with a collar 45 which is adapted to slide within the housing 42. A compression coil spring 47 is provided in the tubular housing 42, one end abutting the end of the housing 42 and the opposite end being engaged by the collar 45. The opposite end of the pin 44 is connected to the free end of the lever 31 previously described. When the lever 31 is moved in a counterclockwise direction (Fig. 3) as has been previously explained, the members 37 and 33 are moved in a corresponding direction. The member 41 corresponds to member 98 in the copending application and its function is described therein.

There is provided a pin 50 within the tubular shaft 22 for engaging one end of the lever 17 and pivoting it in a counterclockwise direction (Fig. 2). Near the lower end of the pin 50 there is provided a collar or flanged portion 51 which is adapted to engage the bottom of the tubular portion of the lever 23 when the pin 50 is raised thereby to move the lever 23 in a vertical plane relative to the shaft 22. The lower end of the pin 50 rests on a lever 52, one end of which is pivotally connected to a bracket 53 by a pin 54. The bracket 53 is fixed to the bottom of the base plate 1 in a manner illustrated in Fig. 2. The opposite end of the lever 52 supports a roller 57 which is adapted to rest on a peripheral surface 58 of the cam wheel 27.

When a record on the turntable 11 is being reproduced, the cam wheel 27 remains stationary in the position shown in Fig. 2. When the pickup arm 13 reaches the tripping groove of a record being reproduced, a tripping mechanism (not shown) initiates the rotation of the shaft 28 through one revolution. The tripping mechanism disclosed in United States Patent No. 2,018,881, patented October 29, 1935, may be incorporated with the driving mechanism previously referred to for initiating the rotation of the shaft 28.

The first operation which the cam wheel 27 performs during its cycle of rotation, is to elevate the stylus 16 of the pickup arm 13 out of engagement with a record being reproduced. This is

brought about by the cam surface 58A moving into engagement with the roller 57 and raising the lever 52 and therewith the pin 50. When the pin 50 is raised, it pivots the lever 17 to lower pin 18 to the dotted line position and to lift the pickup arm 13 and therewith the stylus 16 out of engagement with the record on the turntable. After the stylus 16 of the pickup arm 13 is raised out of engagement with a record on the turntable 11, the roller 57 is in engagement with the surface 58 and the pickup arm 13 is maintained in its raised position. Surface 58 of cam 27 is dimensioned to lift the pin 50 far enough so that pin 18 as well as the stylus is lifted clear of the record. Thereafter, the portion 26A of the cam surface 26 (Fig. 3) engages the pin 24 and moves it, together with the lever 23, in a counterclockwise direction (Fig. 3). When the lever 23 is thus moved after the pin 50 is in its raised position, the ear 30 is in position to enter notch 32 and move the lever 31 and therewith the member 33 (Fig. 3) in a counterclockwise direction. The counterclockwise movement of the lever 23 rotates the tubular shaft 22 and swings the pickup arm 13 in a counterclockwise direction (Fig. 1) to a position beyond the edge of the record on the turntable.

After the cam surface 26A moves out of engagement with the pin 24, the pin 24 is maintained in an outermost position by the cam surface 26. When the inclined portion 26C of the cam surface 26 moves into the path of the pin 24, the levers 23 and 31 are moved in a clockwise direction (Fig. 3) under the biasing action of the spring member 36. The ear 30 and the notch 32 are so arranged that the lever 23 will be moved in a clockwise direction (Fig. 3) sufficiently far to position the stylus of the pickup arm 13 over the initial playing groove of a 10-inch record. However, as has been explained before, if the uppermost record on the turntable is a 12-inch record, the peripheral edge of the record will engage the pin 18 in its lowered position and stop the movement of the pickup arm so that the stylus 16 is positioned over the initial playing groove of the 12-inch record.

As the pickup arm 13 is being moved from its outermost position to a position over the initial playing groove of a record, the eccentric portion 58B of the cam wheel 27 is in engagement with the roller 57. As this eccentric portion 58B moves, it gradually lowers the lever 52 and therewith the pickup arm 13. Thus pin 18 is lowered sufficiently to engage the outer edge of a 12-inch record. When the stylus 16 of the pickup arm 13 is over the initial playing groove of a top record on the turntable, the portion 58C moves into the path of the roller 57 permitting the lever 52 and the pin 50 to lower the stylus 16 of the pickup arm 13 into engagement with the initial playing groove and to permit the lever 17 and the pin 18 to return to the full-line position shown in Fig. 2.

When the lever 52 (Fig. 2) functions to lower the stylus 16 into engagement with the record on the turntable 11, the lever 23 is permitted to move vertically downward out of engagement with the lever 31. Thereafter, the rotation of the cam wheel 27 and the shaft 28 is stopped, and the pickup arm 13 is permitted to move freely over the surface of the record as the stylus 16 tracks the playing grooves.

While there has been described what is at present considered the preferred embodiment of the invention, it will be obvious to those skilled in the art that various changes and modifications

may be made therein without departing from the invention, and it is, therefore, aimed in the appended claims to cover all such changes and modifications as fall within the true spirit and scope of the invention.

What is claimed is:

1. In an automatic phonograph having a rotatable turntable, and a pickup arm for reproducing a record on said turntable; pickup arm control means for positioning said pickup arm at the beginning of a record on said turntable comprising means for elevating said pickup arm above the record on said turntable and lowering it into engagement therewith; means for moving said pickup arm outwardly beyond the periphery of the record on said turntable and returning it toward the center of said turntable; a lever movably connected to said pickup arm and adapted to be moved by said pickup arm elevating means relative to said pickup arm in a plane parallel to the axis of said turntable; and a projection on said lever for engaging the peripheral edge of the record on said turntable for stopping the return movement of said pickup arm, said projection being adapted to move out of engagement with the peripheral edge of the record on said turntable when said pickup arm is moved into engagement with the record.
2. In an automatic phonograph having a rotatable turntable, and a pickup arm for reproducing a record on said turntable; pickup arm control means for positioning said pickup arm at the beginning of a record on said turntable comprising means for elevating said pickup arm above the record on said turntable and lowering it into engagement therewith; means for moving said pickup arm outwardly beyond the periphery of the record on said turntable and returning it toward the center of said turntable; a lever movably connected to said pickup arm and adapted to be moved by said pickup arm elevating means relative to said pickup arm in a plane parallel to the axis of said turntable; a projection on said lever for engaging the peripheral edge of the record on said turntable for stopping the inward movement of said pickup arm, and means operatively associated with said lever for moving said projection out of engagement with the peripheral edge of the record on said turntable when said pickup arm is moved into engagement with the record.
3. In an automatic phonograph having a rotatable turntable and a pickup arm for reproducing a record on said turntable; pickup arm control means for positioning said pickup arm at the beginning of a record on said turntable comprising means for elevating said pickup arm above the record on said turntable and lowering it into engagement therewith, said means including a movable pin; means for moving said pickup arm outwardly beyond the periphery of the record on said turntable and returning it toward the center of said turntable; a spring-biased lever movably connected to said pickup arm and adapted to be moved by said pin relative to said pickup arm in a plane parallel to the axis of said turntable; and a projection on said lever for engaging the peripheral wall of the record on said turntable for stopping the inward movement of said pickup arm, said projection being adapted to move out of engagement with the peripheral wall of the record on said turntable when said pickup arm is moved into engagement with the record.
4. In an automatic phonograph having a ro-

tatable turntable, and a pickup arm for reproducing a record on said turntable; pickup arm control means for positioning said pickup arm at the beginning of a record on said turntable comprising means for elevating said pickup arm above the record on said turntable and lowering it into engagement therewith; means for moving said pickup arm outwardly beyond the periphery of the record on said turntable and returning it

5 toward the center of said turntable, and means operatively associated with said pickup arm and said pickup arm elevating means and movable thereby to project below said pickup arm for engaging the peripheral edge of the record on said turntable for stopping the inward movement of said pickup arm.

JERALD D. WEAVER.
